UNITED STATES PATENT OFFICE.

SVEN P. GUDMUNDSON, OF SAN FRANCISCO, CALIFORNIA.

SAW-FILING DEVICE.

SPECIFICATION forming part of Letters Patent No. 635,476, dated October 24, 1899.

Application filed December 19, 1898. Serial No. 699,748. (No model.)

To all whom it may concern:

Be it known that I, SVEN P. GUDMUNDSON, a citizen of the United States, residing at San Francisco, in the county of San Francisco and State of California, have invented certain new and useful Improvements in Saw-Filing Devices; and I do hereby declare the following to be a full, clear, and exact description of the invention, such as will enable others skilled in the art to which it appertains to make and use the same.

This invention relates to devices for sharpening or filing saws, and is designed for its simplicity and cheapness of construction, and particularly for its certainty and accuracy of operation and its ready adaptability to saws of various forms and pitch of teeth.

A further object of my invention is to improve a device of this character generally, and thereby greatly facilitate the accurate filing of saws for which it is designed.

Other objects and advantages of the invention will appear in the following description, and the novel features thereof will be particularly pointed out in the appended claims.

The objects of my invention I am enabled to accomplish by the means illustrated in the accompanying drawings, in which—

Figure 1 is a perspective view of the device, showing its position relative to an ordinary stiff-back tenon-saw. Fig. 2 is a longitudinal central section of the device. Fig. 3 is a top view of the same. Fig. 4 is a transverse section on the line $x-x$, Fig. 2.

Referring now to the above views by letter, A represents an ordinary stiff-back tenon-saw, held firmly in the ordinary two-jawed clamp B, with the serrated or cutting edge upturned, as shown. Adjustably secured to the rear jaw of clamp B by means of the binding-screws C is the member D, which is provided with outreaching arms E E', the latter loosely carrying the sliding rod F. Secured to the rod F by means of screw a is the member G, to which is pivoted members H and I, one above the other, in the order mentioned. The member H is provided with an integrally-formed guide b, which is adapted to rest between adjacent teeth of the saw. Reaching from the lower member G to the upper member I is the binding thumb-screw J.

This thumb-screw passes through a slot c in member G and a cut-out portion d in member H in such a manner that the three members can be securely bound together after 55 being independently adjusted. Adapted to slide in lugs e, formed on member I, is the rod K, which bears the bracket f. This bracket is formed with rod g parallel to rod K, and further adjustably holds the file h and handle i. Directly beneath the rod g and carried by the member I is the set-screw l.

It is quite manifest that as the parts are in the relative positions shown by reciprocating the handle i and connected file h the latter 65 would cut away the tooth of the saw until the rod g reached the screw l. Should it be desired to file deeper, the screw l must be screwed downward, or vice versa. Now after this portion is filed the bracket f is swung 70 upward in the direction of the arrow in Fig. 4 and the projection b raised out of contact with the saw and placed in the next notch, when the filing of the adjacent tooth proceeds. The distance between the projection 75 b and file h is properly adjusted by resorting to the thumb-screw J.

The members H, I, and G being bound together in the position shown the file is guided diagonally across the saw; but should it be 80 desired to change this pitch the thumb-screw can be loosened and again bound after the proper angle is assumed. Should it be desired to throw the path of the file out of the horizontal, the screws C are resorted to. 85

The construction and arrangement of my device being thus made known, the operation and advantages of the same will, it is thought, be readily understood.

What I claim, and desire to secure by Letters Patent, is—

1. In a device of the class described, the combination with a suitable clamp, a member vertically adjustable relative to said clamp, a tilting member adapted to slide horizontally in said former member, a secondary or tooth-spacing member adjustably pivoted to said tilting member, and a file-bearing bracket pivoted to a third member adjustably connected to said tilting member and said secondary member, substantially as set forth. 95

2. A saw-filing device provided with a suit-

able clamp, a member adjustably connected to said clamp, a rod capable of reciprocation in said member, a secondary member rigidly secured to said rod, a tooth-spacing member 5 adjustably secured to said secondary member, and a reciprocating file-holding bracket connected to said secondary member in such a manner as to be capable of independent motion in a vertical plane, and horizontal

adjustment in a horizontal plane, substantially as set forth.

In testimony whereof I affix my signature in presence of two witnesses.

SVEN P. GUDMUNDSON.
